UNITED STATES PATENT OFFICE.

FREDERICK S. CHASE, OF WATERBURY, CONNECTICUT, ASSIGNOR TO THE WATERBURY MANUFACTURING COMPANY, OF SAME PLACE.

DESIGN FOR A WHISTLE-CASE.

SPECIFICATION forming part of Design No. 24,335, dated May 28, 1895.

Application filed April 22, 1895. Serial No. 546,639. Term of patent 7 years.

To all whom it may concern:

Be it known that I, FREDERICK S. CHASE, of Waterbury, in the county of New Haven and State of Connecticut, have invented a new Design for a Whistle-Case, (Case B;) and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a whistle-case, illustrating my design; Fig. 2, a plan view thereof.

My invention relates to an improved design for a whistle case, and the design consists in the configuration herein described and shown in the accompanying illustrations.

As herein shown the design consists of a cylindrical body A, having a mouth-piece comprising a deep, wide, circumferential

groove A', and a depressed, slightly concaved, concentrically corrugated flange A², containing a diametrical, centrally enlarged orifice A³. The said groove A' is separated from the body by means of a narrow circumferential groove a, while the opposite end of the body has a corresponding parallel groove a'.

The leading features of my design are a 30 whistle having a cylindrical body, and a mouth-piece comprising a wide circumferential groove, and a depressed flange containing an orifice.

I claim—

35 The design for a whistle-case as herein shown and described.

In testimony whereof I have signed this specification in the presence of two subscribing witnesses.

FREDERICK S. CHASE.
